UNITED STATES PATENT OFFICE.

THOMAS E. CLARK AND JAMES E. CLARK, OF DETROIT, MICHIGAN, ASSIGNORS TO
CONTINUOUS TRAIN CONTROL CORPORATION, OF DETROIT, MICHIGAN, A COR-
PORATION OF MICHIGAN.

LOCOMOTIVE CONTROL INSTALLATION.

Application filed December 18, 1926. Serial No. 154,419.

This invention relates to the construction of automatic brake-controlling apparatus for locomotives of railways whose trackway is divided into blocks and equipped, in whole or in part, with controlling stations adapted to impress radio-frequency currents of either of two wave lengths upon the rails, according to the occupancy of the track ahead, and to impress both such currents upon the rails at points where the controlled track joins non-controlled track.

This construction is of the same general character as that shown in our pending application Serial Number 125,907, filed July 30, 1926, but embodies additions thereto and modifications thereof which insure the application of the brakes should any material part of the present application fail for any reason.

In the accompanying drawings, Fig. 1 is a diagram of the electric circuits and instrumentalities connected thereto of a locomotive installation embodying the present invention; and Fig. 2 is a diagram similar to Fig. 1, showing the positions of the parts when the locomotive is running on a trackway which is not equipped with control installations.

Similar reference characters refer to like parts in both views.

The two receptor coils 1 and 2 and the circuits connected thereto are designed to develop potential by reason of electro-magnetic flux or force at the rails of a controlled track which will usually be divided into blocks provided with instrumentalities at their exit ends to impress radio-frequency currents upon the rails, the frequency of such currents being variable according to the condition of the blocks of track in advance, depending on occupancy, broken rails or open switches, the arrangements and construction of such current transmitting devices being such that current of one frequency will be impressed when the block in advance is unoccupied, and a current of another frequency when the block in advance is occupied, but no current being present in that portion of an occupied block between the occupying obstacle and the entrance end of such block. In the present construction, the coil 1 and the circuits connected thereto are intended to respond to the train control current which is present in a block when the next block in advance is unoccupied and will be termed the "clear" circuit, while the coil 2 and its cir-

cuits respond to current when such block in advance is occupied, and will be termed the "caution" circuit. Receptor electron tubes 3 and 4 and operating tubes 5 and 6 are connected into the circuits of these coils and these operating tubes control the opening and closing of electric circuits and relays connected therein to govern the automatic operation of the air brakes of the locomotive or other vehicle equipped with the present installation.

The receptor coils 1 and 2 are preferably mounted on the leading truck of the locomotive near the rails so as to pass through the energized fields of greatest electromagnetic flux around the rails, and the filament circuits of the tubes 3 to 6 inclusive include loops which extend down to and around these collector coils so that should either be torn from its mounting, the circuit of the tube filaments will be broken. This circuit is over wires 7 and 8, relay 9, wires 10, 12, 13, 14 and 15, filament of tube 3, wire 17, filament of tube 5, wire 18, filament of tube 6, wire 19, filament of tube 4, wire 20, main return wire 21 and wire 22.

The plate current is derived from a transformer or from the dynamotor 24 which is energized by current derived from the generator G over wires 7-26 and 27-21. The wire 30 connects to the primary windings 31 of transformers 32 and 33 and then to the plates of tubes 3 and 4. Wires 34 and 35 extend from the wire 30 to relays 36 and 37 and from these relays, wires 38 and 39 connect to the plates of the tubes 5 and 6. The filaments of the tubes are connected by the wires 17, 18 and 19, and the wire 18 connects to the dynamotor by means of the wires 40 and 41, resistance 42, wires 43 and 44, resistance 45, wire 46, resistance 47 and wire 48.

The two receptor coils connect to adjustable condensers 51 and 52 by means of wires 53, 54, 55 and 56. The wire 53 connects to the grid of the electron tube 3 and the wire 56 to the grid of the tube 4 while the wires 54 and 55 adjustably connect to the resistance 42 which connects to the negative end of the resistance 57 by means of wire 58. As the currents in these receptor coil circuits are usually weak, the electron tubes shown are made use of. If the current in these receptor coil circuits were sufficiently strong, the second tubes 5 and 6 might be dispensed with.

In order that all instrumentalities of this installation may move to neutral or "danger" position should any breakage or failure occur, provisions are so made that the control relays 36 and 37 will function only when proper electro-magnetic conditions exist in the track rails and in either receptor circuit or both. Means are therefore provided to normally charge the grids of each electron tube with a sufficient negative potential in relation to the filament to obstruct to some extent the passage of the direct current between the filaments and the plates of the tubes and thus place a low load on these tubes and prevent the cores of the transformers 32 and 33 from becoming saturated.

The resistance 57 connects to the positive side of the dynamotor by means of wire 30 and is preferably of about 5000 ohms, much greater than that of resistances 42, 45 and 47 combined. It therefore so influences resistance 42 that this may be considered as an extension of the negative end thereof in relation to the filaments. The plates of the four tubes also connect to the positive wire 30 as above described, and these plates are therefore positive relative to the filaments of these tubes which connect to the negative wire 48 through the resistances 42, 45 and 47.

A negative bias of potential is impressed upon the grid of tube 3 by reason of the wire 54 engaging the resistance 42 on the negative side of the filament connection 41, the circuit to this grid being over this wire 54, receptor coil 1 and wire 53. Similarly, the circuit to the grid of tube 4 consists of the wire 55 engaging resistance 42, coil 2 and wire 56. An electro-magnetic flux around the track rail is responded to by a receptor circuit and an alternating potential is built up in the receptor circuit which alternates at the frequency to which this receptor circuit is tuned. This alternating potential acts on the grids of tubes 3 and 4 to cause them to be first less negative and then more negative and this action causes the current in the plate circuit to increase and decrease in unison with the frequency impressed on the grid circuit. So long as direct constant current passes from filament to plate in tubes 3 and 4, no current is induced in the secondary windings 60 and 61, but when a potential is induced in the receptor circuit it changes the bias on the grid of tube 3 or 4; the current passing from filament to plate of such tubes is increased and decreased, resulting in an alternating current being induced in the proper secondary winding.

Negative bias is also present in the grids of tubes 5 and 6, this bias of the former being derived from the connection 46 between the resistances 45 and 47, while that of the tube 6 is derived from the connection 43 between resistances 42 and 45. So long as this bias continues constant in tube 5, its plate current

is somewhat obstructed, but whenever the current is varied in the plate circuit of tube 3, induced alternating current is set up in the secondary winding 60 of transformer 32, the positive halves thereof reducing the negative bias of the grid of tube 5 so that current may flow in the plate circuit of that tube and energize relay 36. In the same manner, relay 37 responds to oscillating current in the circuit of receptor coil 2.

The usual grid leaks 63 are connected into the grid circuits of tubes 5 and 6, so that, if the secondary windings 60 and 61 burn out, the negative bias of potential referred to above is not affected thereby. Condensers 64 are positioned wherever necessary to bypass and confine the radio-frequency currents to their proper circuits. A by-pass condenser 65 bridges between the main positive wire 30 and negative wire 48 and a condenser 67 bypasses the resistance 57. Small switches 68 may be installed wherever desirable to afford an opportunity for the use of current meters. A wave trap 66 may be connected into each of the receptor coil circuits to eliminate interference from any electro-magnetic waves excepting those for which that particular receptor circuit is tuned.

In the following description, whenever an armature is specified, it will be denoted by a small letter together with the reference numeral of its relay.

When receptor coil 1 intercepts electro-magnetic flux of proper frequency, current from the plate of tube 5 energizes relay 36, and when coil 2 intercepts proper flux, relay 37 is energized. When neither receptor coil intercepts flux for which its circuit is tuned, neither of these control relays is energized and their armatures are in dropped position.

Fig. 1 shows the positions of the several armatures while control relay 36 is energized, which is while the locomotive is proceeding under "clear" track conditions. In tracing the several circuits, wires 8 and 21 may be taken as the positive and negative wires respectively. The control relay 36 when energized, closes the circuit to the main "clear" relay 74 from wire 8 over wires 70 and 71, pneumatically controlled switch 72, wire 73, main "clear" relay 74, wire 75, armature 36^a and wires 76 and 77 to negative wire 21. If control relay 37 were energized, current would pass through main "caution" relay 78 from wire 73 and then over wire 79, armature 37^a and wires 76 and 77 to wire 21.

Three electric signal lamps 80, 81 and 82 are mounted in the locomotive cab, being preferably green, yellow and red respectively, to indicate "clear", "caution" and "danger", and these lamps have a common wire 83 connected to wire 8. The return circuit of green lamp 80 is over wire 84, dropped armature 78^a, wire 85, and armature 74^a to wire 21. This lamp therefore receives current only

when relay 74 is energized and relay 78 is de-energized.

An electro-pneumatic valve 90, of well known construction and commonly known as an E. P. valve, is adapted to cause reduction of the air pressure within the control valve 89 of the brake system, and within the casing of this E. P. valve is a magnet 91 adapted to draw down its armature 92 from which a stem extends down to the valve 94, which is held on its seat while the magnet 91 is energized.

The construction and operation of this E. P. valve and of the control valve is fully described and claimed in application Serial Number 153,258, filed by William L. Coop and Charles B. Stone on December 8th, 1926, but the connection between that construction and the present control system should be sketched briefly.

When a train is to be moved under clear conditions, at which time the E. P. valve is energized, the engineer swings the handle of this train valve to permit air to fill the brake pipe and thus release the brakes. This causes a slow accumulation of pressure within the chamber 97, which is connected to the train pipe, and through the passage 99 into the top of the cylinder 100 above the piston 101.

This brake pipe pressure is less than the pressure within the main reservoir (not shown) to which a pipe 106 connects. Air from the main reservoir flows into the cylinder 107 through this pipe 106 and through a passage into the chamber 126. The piston 109 in the cylinder 107 connects to the valve 111.

The piston 101 is attached to a valve stem 118 which carries a valve 119, which normally is closed. A second cylinder 121 adjacent and preferably in alignment with the cylinder 100 contains a piston 122, normally held upward. This cylinder is formed with any desired number and type of openings 124 and the lower end of the stem 125 which connects to the piston 122 is attached to the switch member 72 which connects the wires 71 and 73 when in the position shown.

When the magnet 91 of the E. P. valve is deenergized, air pressure in the chamber 126 lifts the valve 94 and permits air to flow from the cylinder 107 to the pipe whistle 132 which sounds to indicate that this valve is de-energized.

Normally, the pressure in the cylinder 107 is that of the main air reservoir and in the chamber 97 is that of the train pipe, which is lower than that in the cylinder 107. When the E. P. valve is de-energized and air flows from the cylinder 107, the greater pressure in the chamber 97 forces the piston 109 to the right in Fig. 1, cutting off the connection between the train pipe and the cylinder 100 and permitting air to flow from cylinder 100.

The reduction of the pressure in the cyl-

inder 100 above the piston 101 requires a pre-determined time interval before the pressure below this piston lifts the piston and the valve 119 connected thereto. This time interval is provided to permit the E. P. valve to be re-energized to forestall the application of the brakes, as will be explained later on. Should the E. P. valve remain de-energized beyond this predetermined time interval, the piston 101 and valve 119 will lift, and the train pipe air will rush down onto piston 122 in cylinder 121, forcing down this piston below the holes 124 which will permit the free discharge of the train line air. When this piston is forced down, the switch 72 is opened, and with it the circuit of wires 71 and 73. Switch 72 remains open until the pressure in the train pipe is so reduced that the piston 122 is no longer held down by the pressure above it. As this air switch is completely enclosed, it cannot be closed manually.

Referring now to Fig. 1, it will be noticed that the normal energizing circuit of the E. P. valve includes wire 8, wire 70, switch 65', wire 146, magnet 91, wire 147, armature 90^a, wire 148, dropped armature 78^a, wire 149, armature 74^a, wire 150, forestalling key 151 and wires 21 and 22, and that this circuit is held closed by relay 9 which is energized so long only as the receptor coils 1 and 2 are in operative position and all the filament circuits of the electron tubes are unbroken. So long, therefore, as all the parts are in good condition and the control relay 36 is energized, the E. P. valve will remain energized.

The position of the several parts when receptor coil 2 and its circuit cause the energization of control relay 37, is shown in Fig. 2. Current flows over common wire 83 to yellow lamp 81 and over wire 152, armature 105^a, wire 153, dropped armature 74^b, wire 154, dropped armature 161^b, wire 155, starting key 156, wires 157 and 158, dropped armature 74^d and wires 21 and 22. This lamp 81 therefore receives current so long as relay 78 is energized and relay 74 is de-energized. As soon as relay 78 is energized, its lifted armature 78^a opens the circuit of the E. P. valve, and unless this circuit is restored or another is made for the E. P. valve before the piston 101 lifts, the brakes will be applied.

A forestalling circuit is established by momentarily depressing the forestalling key 151 which closes the circuit consisting of wires 8, 70 and 71, switch 72, wire 73, holding relay 160, wire 159, armature 74^b, wire 163, depressed key 151, and wires 21 and 22. It will be observed that this circuit cannot be made if the operation of the key has been delayed until switch 72 has been moved down by train pipe pressure. The energized relay 160, which is slow releasing, attracts its armature *a* and closes a circuit from this relay over wire 159, armature 160^a, wires 164, 148 and 167, armature 160^c, wire 155, key 156, wires 157, and 130.

- 158, armature 74^a, and wires 21 and 27. The relays 160 and 161 are slow releasing and when caution current is picked up relay 160 is energized while relay 161 is de-energized.
- 5 When no current is picked up, both relays are energized, as will be explained later on.

The new circuit for the E. P. valve comprises wire 147, armature 9^a, wires 148 and 167, armature 160^c, wires 168 and 155, key 156, wires 157 and 158, dropped armature 74^a and wires 21 and 22. This circuit will remain closed so long as the holding circuit is kept closed until opened by armature 74^a being lifted by its relay which would result in the first described normally energized circuit being closed.

If no current is present in either relay 36 or 37, all the armatures of relays 74, 78, 160 and 161 will be in dropped position and current will pass to the red lamp 82 and thence over wire 170, armature 78^a, wire 153, armature 74^c, wire 154, armature 161^b, wire 155, key 156, wires 157 and 158 and armature 74^a to wire 21. The energizing circuit of the E. P. valve is opened by armature 74^a dropping.

The key 156 is preferably so placed at some point on the locomotive that it can be reached only by a person standing on the ground which necessitates the locomotive being brought to a stop when the red lamp receives current which occurs when the locomotive enters an occupied block when neither of the two control relays is energized. When this key is depressed, current passes from wire 73 to relay 161 and over wire 171, key 156, wires 157 and 158 and dropped armature 74^a to wire 21, energizing relay 161 and closing a stick circuit therefor over wire 171, armature 161^a, wires 172 and 173, dropped armature 78^b, wire 166, dropped armature 74^a, wire 150 and key 151 to wire 21. Key 156 is now released and moves to normal position. Energized relay 161 now closes a circuit for the E. P. valve over wire 147, armature 9^a, wire 148, armature 161^c, wire 155, key 156, wire 158 and dropped armature 74^a to wire 21. The brakes which were automatically applied when the locomotive entered the occupied block may now be released by the engineer and the locomotive may now proceed. When no current is received by either receptor coil, which occurs under danger conditions, the E. P. valve causes the piston 122 to open the switch 72 which causes the brakes to be applied and the train to come to a stop, which it must always do when this switch opens. The switch remains open until the train pipe pressure falls so low that the spring under piston 122 can lift this switch. After this switch is opened the depression of key 151 has no effect. Neither has it any effect when both relays 74 and 78 are de-energized. But after this switch is closed the key 156 may be depressed and the engineer may release the brakes.

At such points where the locomotive passes from a controlled section of track to one not controlled, means are provided for simultaneously impressing both control currents on the rails at the exit end of the controlled track. This causes both control relays 74 and 78 to become energized and the circuit of the E. P. valve to be opened by armature 78^a. Key 151 must now be depressed and a circuit for relay 161 becomes closed, consisting of wires 8, 70 and 71, switch 72, wire 73, relay 161, wires 171 and 174, armature 74^b, wire 163, depressed key 151 and wire 21. Energized relay 161 raises its armature *a* and as soon as key 151 is released, closes a stick circuit over wire 171, armature 161^a, wires 172 and 173, armature 78^a, wire 149, armature 74^a, wire 150 and key 151 to wire 21. It also closes a circuit for the E. P. valve comprising wire 147, armature 9^a, wire 148, armature 161^c, wire 155, key 156, armature 78^c, wire 85 and armature 74^c to wire 21. The stick circuit and the circuit for the E. P. valve will remain closed until the locomotive again passes onto controlled trackway.

The starting key 156 will also be used when the locomotive is to be started in a round-house, being depressed after the generator G and dynamotor 24 have reached their usual speed and current output to complete a circuit for the E. P. valve which, when energized, permits charging of the main air reservoir. The red lamp 82 receives current until the key 156 is depressed and thus indicates that relay 161 has not closed the circuit of the E. P. valve. But as soon as relay 161 is energized, its armature *b* opens the circuit to this lamp. As the locomotive is not connected to a train, the train pipe and chamber 97 have no pressure.

Should either of the receptor coils be broken or any one of the filaments of the tube become inoperative, no plate current will pass to the relays 36-37 and the circuits controlled thereby will become inoperative to carry current to the E. P. valve. Failure of the transformers 32 and 33 or of any of the circuits controlled by the relays 36 and 37, or of the generator or dynamotor will have the same effect.

It will be noticed that the wire 40 extends from wire 18 which connects the filaments of the tubes to the wire 41 and that the breaking of any one of these wires will open all the plate circuits and render relays 36 and 37 inoperative. The circuit between wire 41 and the dynamotor includes the resistances 42, 44, 45 and 47 and the wires 43, 44, 46 and 48, so that should there be a break at any point in this circuit, the plate current of all the tubes will fail.

Vacuum tubes 3 and 4 are biased to that potential which gives the maximum amplification for the style tube used. This potential is determined by selecting that point on the

grid voltage plate current curve of the tube where the tube operates on the straight part of the curve. To save the use of high current through the tube it is advisable to normally

5 work on that part of the straight line which is on the negative grid potential of the center line. This will give a stand-by of from 6 to 9 mills in a type PR 10A tube.

In practice the proper potential is found 10 by placing the tubes in their respective circuits and moving the grid return to that point on the testing resistor which gives maximum amplification for the least amount of current flowing in the plate circuit of the tube 3 or 4.

15 Tubes 5 and 6 are highly negative biased to stop the flow of plate current so that any decrease in the negative potential on this tube will cause current to flow in its plate circuit. This does not necessarily mean that the grid 20 of this tube has been made positive. Current will flow when the negative potential on the grid is decreased and the amount of current that will flow is governed by the style of tube used and the resistance in this plate circuit.

25 Resistance 57 is connected with resistances 42, 45 and 47 through wire 58 to constitute a resistor which is connected across the high voltage terminals of the dynamotor 24 and the grid bias for the various tubes is obtained 30 by taking taps off from this resistor at points that give the proper potential for the most efficient operation of the tubes.

This combination of resistances is used to 35 obtain both the plate current and the grid bias potentials. The positive feed to the various plate circuits is taken off from wire 30 and the negative plate connection to the filaments is taken off at wire 18 which connects to the end of resistance 42. This point 42 is 40 the negative plate current connection to the filament and the positive current connection for the various grid circuits. The various grid potentials are obtained by moving from the connection of wire 18 with resistance 42 45 toward the negative terminal of the dynamotor. It will be seen that the negative return for the plate current is through the resistance 42 over 43, wire 44, resistance 45, wire 46, resistance 47 to the negative terminal of the 50 dynamotor and should this circuit be broken at any point in the circuit the negative plate connection will be broken and no current will flow in the plate circuit of the various tubes.

The system shown and described may 55 therefore be said to be biased on the side of safety.

The details of construction and the proportions of the parts of this locomotive installation may all be changed by those skilled 60 in the art without departing from the spirit of our invention as set forth in the following claims.

We claim:—

65 1. In combination with a current source, a pair of electro-magnetic elements, an elec-

tron tube for each electro-magnetic element and embodying a plate electrically connected to such element, a filament for each tube connected to said current source and a grid between the plate and filament, a receptor electron tube for each of the first named tubes, means to establish negative bias of potential 70 on the grids of the several tubes, receptor coils adapted to receive oscillating currents, electric circuit connecting said coils to the 75 grids of the receptor tubes, and a circuit between the current source and the filaments of said tubes including loops extending around both of said receptor coils.

2. In combination with a current source, a 80 pair of electro-magnetic elements, an amplifying electron tube for each electro-magnetic element and embodying a plate electrically connected to such element, a filament for each tube connected to said current source and a 85 grid between the plate and filament, a receptor electron tube for each of said first named tubes, means to establish negative bias of potential in the grids of the several tubes, receptor coils adapted to receive oscillating 90 currents, electric circuits connecting said coils to the grids of the receptor tubes, and a wave trap connected into each of said receptor coil circuits to block interference by the electro-magnetic waves for which the other 95 receptor coil circuit is tuned.

3. In combination with a current source, a train-control valve adapted to be held closed by current from said source, a whistle connected to said valve and adapted to sound 100 when said valve is open, circuits between said current source and said valve, receptors for radio-frequency currents and instrumentalities controlled therby for opening and closing said circuits, said instrumentalities embodying electron tubes relays and circuits between the tubes and relays, a manually operable key adapted to act in conjunction with the instrumentalities controlled by one of said receptors to close one of said circuits, 105 and an air switch controlled by said valve and adapted to open the circuits between it and the current source after the valve has been opened a predetermined length of time.

4. In combination with a current source, a 110 pair of relays connected thereto, an electron tube for each relay embodying a plate connected to the relay, a resistance circuit embodying a series of resistances and connections to both poles of the current source, a 115 connection between the filaments of said tubes and said resistance circuit, and connections extending from the grids of said tubes to said resistance circuit on the negative side thereof relative to the filament connection so as to 120 normally produce a negative bias of potential 125 in the grids.

5. In combination with a current source, a 130 pair of relays and circuits connecting one pole of each to the current source, an amplifying

ing electron tube for each relay embodying a plate connected to the other pole of the relay, a complete resistance circuit embodying resistances in series and connections to the current source, receptor electron tubes and transformers connected to the plate circuits thereof, a connection between the filaments of said tubes and said resistance circuit, secondary windings of said transformers connected to the grids of said first named tubes, connections extending from the grids of all said tubes to said resistance circuit on the negative side thereof relative to the filament connection so as to normally produce a negative bias of potential in the grids, and receptor coils and circuits thereto connected to the grids of said receptor tubes.

6. In combination with a current source, a train-control valve adapted to be held closed by current from said source, a circuit between the current source and said valve, a receptor for high-frequency current and instrumentalities controlled thereby for closing said circuit, a second circuit between the current source and said valve, a forestalling key in said circuit, a second receptor for high-frequency current and instrumentalities controlled thereby for closing said second circuit when said key is moved to circuit-closing position, a third circuit between the current source and said valve adapted to be closed by said key and the instrumentalities controlled

by both of said receptors, and an electromagnetic switch controlled by said valve for opening the energizing circuit of said valve should a predetermined time elapse between the opening of said valve and the closing of said key.

7. In combination with a current source, a pair of control relays and the armatures thereof, a current source, a train-control valve normally held closed by current from said source, a forestalling key and circuits between the current source and said valve whereby current will flow to said valve when one of said relays is energized, and when the key is actuated and the second relay is energized, a third relay and circuits between its armatures and said valve, key and current source which circuits are closed when both the first named relays are deenergized and the key is actuated, an electro-pneumatic switch controlled by said valve for opening the energizing circuit of said valve should a predetermined time elapse between the opening of said valve and the closing of said key, and a fourth relay and circuits between its armatures and said valve, key and current source which circuits are closed when both the first named relays are energized and the key is actuated.
